R. C. BENDER.

INVOICE HOLDER.

APPLICATION FILED JULY 5, 1917.

1,256,867.

Patented Feb. 19, 1918.

Inventor:
Robert C. Bender,
By *J. C. Commins, Atty.*

UNITED STATES PATENT OFFICE.

ROBERT C. BENDER, OF ST. LOUIS, MISSOURI.

INVOICE-HOLDER.

1,256,867.

Specification of Letters Patent. Patented Feb. 19, 1918.

Application filed July 5, 1917. Serial No. 173,676.

To all whom it may concern:

Be it known that I, ROBERT C. BENDER, a citizen of the United States, residing at St. Louis, Missouri, have invented a certain new and useful Improvement in Invoice-Holders, of which the following is a full, clear, and exact description, such as will enable others skilled in the art to which it appertains to make and use the same, reference being had to the accompanying drawings, forming part of this specification.

My invention relates to an invoice holder, the principal object of my invention being to provide a comparatively simple, inexpensive holder which is adapted to receive and hold in a convenient manner invoice sheets or record slips such as are usually employed by business houses and particularly those engaged in the selling and distributing of merchandise.

A further object of my invention is to provide a holder to which the invoice sheets can be easily and quickly applied or from which they can be readily removed, said invoice sheets being retained upon the holder in such a manner as to permit portions of the sheets to be readily raised or folded over in order to show certain data on the lowermost invoice sheets, this provision being essential in order to facilitate the work of the book-keeper or clerk in making out the customers' statements and in checking off the cash receipts, bills payable and the like. After being removed from the holder, the invoices are placed in suitable containers and constitute a permanent record.

With the foregoing and other objects in view, my invention consists in certain novel features of construction and arrangement of parts, hereinafter more fully described and claimed, and illustrated in the accompanying drawings, in which—

Figure 1 is a front or face view of an invoice holder of my improved construction and showing an invoice sheet in position thereupon;

Fig. 2 is an elevational view of the rear side of the holder with a removable card positioned thereupon, a portion of said card being broken away;

Fig. 3 is a cross section taken approximately on the line 3—3 of Fig. 1;

Fig. 4 is an end view of the invoice holder, the same being bent transversely so as to permit the ready insertion or removal of the invoice sheets;

Fig. 5 is an enlarged detail section taken approximately on the line 5—5 of Fig. 1;

Fig. 6 is an enlarged detail section taken approximately on the line 6—6 of Fig. 1.

Referring by numerals to the accompanying drawings which illustrate a practical embodiment of my invention, 10 designates the body of the holder, said body being formed of a rectangular section of comparatively thin sheet metal which is resilient to a certain degree, and stamped from the material forming said body are two or more transversely disposed retaining clips or fingers 11, the same being provided with upwardly bent portions 12 immediately adjacent to the points where said fingers unite with the body 10.

Formed in the central portion of the body 10 above, below and between the fingers 11 are longitudinally disposed slots 13 which permit the body 10 to readily flex or bend transversely when pressure is simultaneously applied to the side edges of the body and which operation takes place when it is desired to place an invoice sheet upon the holder or remove said sheet therefrom. (See Fig. 4.)

Pressed upwardly from the body 10 in alignment with each other and with the upwardly bent portions 12 of the fingers 11 is a row of comparatively small vertically disposed lips 14, the same performing the functions of stops for the left hand edges of the invoice sheets placed on the holder and beneath the retaining fingers 11.

Pressed upwardly from the upper portion of the body 10 is a series of inverted L-shaped lips 15, the same serving as keepers or retaining members for a card A, which latter is printed with suitable headings adapted to receive data pertaining to the invoice sheets placed on the holder.

Pressed downwardly from the material forming the body 10 of the holder adjacent to the side edges and bottom thereof are substantially L-shaped retaining lips 16, the same being adapted to form retaining means for a sheet or card B, the same being printed with suitable headings for data relative to the invoice sheets positioned upon the holder.

The invoice sheet or sheets C are positioned on the front face of the holder with their left hand edges against the aligned stops 14, said invoices being held upon the holder by the retaining fingers 11. Thus,

the invoices are firmly held in a convenient manner and the right hand portions of the sheets can be readily turned upward and over toward the left when the bookkeeper or proper clerk is transferring the data from said sheets to the proper books or permanent records.

To place an invoice sheet upon the holder or to remove a sheet therefrom, it is only necessary to engage the side edges of the holder between the thumb and fingers and press said edges toward each other, thereby flexing or bending the central portion of the body of the holder upward as illustrated in Fig. 4, thereby raising the free ends of the retaining fingers 11 and with said fingers so positioned, it is a comparatively easy matter to insert or remove the invoice sheet.

The sheets or cards A and B which are retained upon the holder of the lips or retaining members 15 and 16 are adapted to receive data relative to the customers whose invoices are placed upon the holder.

The card A which is readily removable from the retaining lips 15 is preferably provided with the customer's name, rating, shipping address, and the like, and is retained on the holder as long as there are any invoices thereupon. When all of the invoices have been removed from the holder and the account is inactive, the corresponding card is removed from the holder and delivered to the sales manager who can follow up the account. Obviously, when the invoices and address card are removed from the holder, the latter can again be put in service.

An invoice holder of my improved construction is comparatively simple, can be easily and cheaply manufactured and provides an efficient and convenient time and labor saving device for all business houses using invoice sheets and the like.

It will be readily understood that minor changes in the size, form and construction of the various parts of my improved invoice holder can be made and substituted for those herein shown and described, without departing from the spirit of my invention, the scope of which is set forth in the appended claims.

I claim:

1. A device of the class described comprising a plate, a plurality of retaining fingers transversely arranged thereupon, and there being a centrally arranged longitudinally disposed row of openings formed in

said plate to permit the same to be readily bent transversely.

2. A device of the class described comprising a plate, a plurality of retaining fingers transversely arranged thereupon, there being a centrally arranged longitudinally disposed row of openings formed in said plate to permit the same to be readily bent transversely, and a row of stops formed on said plate adjacent to one edge thereof.

3. A device of the class described comprising a plate, a plurality of retaining fingers transversely arranged thereupon, there being a centrally arranged longitudinally disposed row of openings formed in said plate to permit the same to be readily bent transversely, and sheet retaining lips projecting upwardly and downwardly from said plate.

4. A device of the class described comprising a plate, a plurality of retaining fingers transversely arranged thereupon, there being a centrally arranged longitudinally disposed row of openings formed in said plate to permit the same to be readily bent transversely, a row of stops formed on said plate adjacent to one edge thereof, and sheet retaining lips projecting upwardly and downwardly from said plate.

5. In a device of the class described, a body comprising a plate of resilient material, there being a centrally arranged longitudinally disposed row of openings formed in said plate to permit the same to be readily bent transversely, and sheet retaining means on the face of said plate.

6. In a device of the class described, a body comprising a plate of resilient material, there being a centrally arranged longitudinally disposed row of openings formed in said plate to permit the same to be readily bent transversely, and transversely disposed sheet retaining fingers pressed upwardly from the body of said plate.

7. In a device of the class described, a body comprising a plate of resilient material, there being a centrally arranged longitudinally disposed row of openings formed in said plate to permit the same to be readily bent transversely, transversely disposed sheet retaining fingers pressed upwardly from the body of said plate, and sheet retaining lips pressed upwardly and downwardly from the body of said plate.

In testimony whereof I hereunto affix my signature this 3d day of July, 1917.

ROBERT C. BENDER.
